(57) **CLAIM**

The ornamental design for a tablet computer, as shown and described.

DESCRIPTION

The present application is related to U.S. Design patent application Ser. No. 29/611,586, entitled Open Laptop Computer, and to U.S. Design patent application Ser. No. 29/611,587, entitled Closed Laptop Computer, filed concurrently herewith, the entire disclosures of which are incorporated herein by reference.

FIG. 1 is a front perspective view of a tablet computer according to a first embodiment of our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof;

FIG. 7 is a bottom elevation view thereof;

FIG. 8 is a rear perspective view thereof;

FIG. 9 is a front perspective view of the tablet computer according to a second embodiment of our design;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top elevation view thereof;

FIG. 15 is a bottom elevation view thereof; and,

FIG. 16 is a rear perspective view thereof.

The broken lines shown in the drawings depict portions of the tablet computer that form no part of the claimed design.

1 Claim, 12 Drawing Sheets
